Gagnebin & Hayes[57] **CLAIM**The ornamental design for a portion of a headset cable,
as shown and described.**DESCRIPTION**FIG. 1 is a cross-sectional view of a headset cable taken
perpendicular to the cable as it would be seen any
where along the length of the cable. The broken line
showing of the cable and spool is included for the pur-
pose of illustrating environmental structure only and
forms no part of the claimed design.*FIG. 1*
